[57] CLAIM

The ornamental design for a concentrating solar radiation collector assembly, as shown and described.

DESCRIPTION

FIG. 1 is a top right front perspective view of a concentrating solar radiation collection assembly, showing my new design;

FIG. 2 is a front elevational view thereof;

FIG. 3 is a side elevational view, the opposite side being identical thereto;

FIG. 4 is a rear elevation and view thereof;

FIG. 5 is a lower right perspective view of the concentrating solar radiation collector assembly;

FIG. 6 is a top plan view, the bottom being identical thereto;

FIG. 7 is a sectional view taken along line 7—7 shown in FIG. 2.
